UNITED STATES PATENT OFFICE.

CAID H. PECK, OF WAVERLY, NEW YORK, ASSIGNOR TO IMPERIAL PNEUMATIC TOOL COMPANY, OF ATHENS, PENNSYLVANIA, A CORPORATION OF NEW YORK.

HANDLE FOR PNEUMATIC TOOLS.

SPECIFICATION forming part of Letters Patent No. 758,100, dated April 26, 1904.

Application filed January 16, 1904. Serial No. 189,331. (No model.)

To all whom it may concern:

Be it known that I, CAID H. PECK, a citizen of the United States of America, and a resident of Waverly, county of Tioga, State of New York, have invented certain new and useful Improvements in Handles for Pneumatic Tools, of which the following is a specification, reference being had to the accompanying drawings, forming a part thereof.

My invention relates to improvements in pneumatic tools, and particularly to handles therefor.

The term "handle" is often applied to that portion of pneumatic tools comprising the head-block and the handle proper, and in the title and general description of this invention I have adopted and applied the term as a matter of convenience, while in the more precise claims I have carefully differentiated between the head-block and the handle proper.

In the most approved form of pneumatic tools at present in use it is customary to provide means for controlling passage of motive fluid to the pneumatic tool by means of an operating-lever having a thumb-piece in proximity to the grasping portion of the handle, so that operation of the tool may be readily controlled by movement of the thumb of the hand supporting the tool.

In my present invention I provide the head-block with an inlet-duct and mount a valve for controlling the inlet-duct in the said head-block. I then provide the grasping portion of the handle with an operating-lever and provide an intermediate lever between the operating-lever and the stem of the valve.

In the preferred form of my invention I provide a valve-seat separate from the head-block and arranged to be removably secured therein, and I provide the valve with a long stem, which penetrates the head-block laterally, so that its outer end may be engaged by the intermediate lever. The connection for the flexible hose arranged to convey the supply of motive fluid preferably comprises a boss extending rearwardly from the head-

block, so that the valve and the valve-seat may be readily removed and replaced when desired. The valve is of the "puppet" form having a puppet-head arranged to engage a valve-face to which it is fitted, and the portion of the valve-stem immediately beneath the puppet-head is tapered, while the portion of the valve-seat surrounding it is cylindrical. By this arrangement a very sensitive graduation of supply in the movements of the valve is obtained in a very simple manner. The operating-lever is arranged in a slot in the grasping portion of the handle with the thumb-piece facing outwardly. The front portion of the operating-lever has a cam-face for engaging the rear end of the intermediate lever. The intermediate lever is pivoted in a slotted portion of the shank of the handle or that part of the handle which connects the grasping portion with the head-block. By properly shaping the cam-face of the lever the valve may be controlled to the best advantage with the minimum exertion. The valve is so arranged as to balance, so far as fluid-pressure is concerned, while being operated, so that there is no resistance from the motive fluid upon the operating-lever at such times.

The object of my invention is to improve and simplify pneumatic tool-handles, render the parts easy of access and simple of manufacture, to improve the sensitiveness of the valve control, and to reduce the length of the air-inlet duct to a minimum.

To these ends my invention consists in certain details of construction and combination of parts, as will hereinafter be fully pointed out.

I will now proceed to describe a device embodying my invention and will then point out the novel features in claims.

In the drawings, Figure 1 is a view in side elevation of a pneumatic tool-handle embodying my invention. Fig. 2 is a view in central vertical section therethrough. Fig. 3 is an end view of same.

The handle as a whole comprises a head-block 1, having an external screw-threaded

extension 2, by which it may be secured to the tool proper, a grasping portion 3, and a shank 4. The head-block 1 is recessed at 5 to form a valve-chamber and receive a valve-seat 6, fitted thereto and secured in place by a screw-threaded connection 7. A boss 8 projects rearwardly from the head-block and is arranged to receive the end of a flexible hose arranged for conveying motive fluid to the tool. The inlet-duct 9 passes through the boss into the valve-chamber 5. The head-block is bored out at 10, such bore opening into the recess 5, to which the valve-seat is fitted at one side and at the other side communicating with a smaller bore 11, arranged for receiving and guiding the stem of the controlling-valve. The controlling-valve comprises a puppet-valve head 12, fitted to a suitable valve-face in the valve-seat 6, a stem 13 projecting rearwardly of said valve-face, a tapered neck 14 immediately in front of said valve-face, and a valve-stem 15 fitted to the bore 11. The valve-stem 15 penetrates to the exterior of the bore 11 into a slot 16 transverse of the head-block and extending longitudinally through the shank 4. A similar slot 17 is arranged in the grasping portion of the handle 3, and an operating-lever 18 is pivotally mounted at 19 in said slot 17. The operating-lever 18 has a thumb-piece 20, which projects rearwardly of the handle, an operating cam-face 21, and a portion 22, arranged to abut against the wall of the slot 17, so as to form a stop, limiting the movement of the lever in one direction. An intermediate lever 23 is pivotally mounted at 24 in the slot 16, the rear end of the lever engaging the cam-face 21 of the operating-lever 18 and the front end of the lever resting against the outer end 40 of the valve-stem 15.

When the grasping portion of the handle is grasped in the usual way, the thumb will naturally rest upon the thumb-piece 20 of the operating-lever 18. A slight pressure of the thumb will cause the cam-face 21 to so act upon the intermediate lever 23 as to raise the rear end, depress the forward end, and hence depress the controlling-valve, so as to withdraw the valve-face 12 from its seat. Because of the tapered formation of the neck 14 the first movement of the controlling-valve will only permit a small quantity of motive fluid to pass. Further pressure upon the thumb-piece will cause the valve to be opened wider and wider, whereby a graduated admission is obtained, giving easily and readily the required amount of admission. A spring 25 opposes movement of the valve and tends to return same to its seat. It will be noted that the valve is balanced as to fluid-pressure while being operated, so that there will be no tendency for the motive fluid itself to force the valve to its seat, a light spring only being em-

ployed for this purpose. The action of the valve by reason of this will be very much more sensitive and delicate than if opposed by the motive fluid.

What I claim is—

1. In a pneumatic tool the combination with a head-block having an air-inlet duct therein, of a valve mounted in said head-block controlling said air-duct, a handle connected to said head-block, an operating-lever mounted in said handle and having a wedge-action cam-face, and an intermediate lever between the stem of said valve and said operating-lever, arranged to engage said cam-face and be operated by the wedge action thereof.

2. In a pneumatic tool the combination with a head-block having an air-inlet duct therein, of a valve mounted in said head-block controlling said air-duct, a handle connected to said head-block, an operating-lever mounted in said handle and having a wedge-action cam-face, and an intermediate lever between the stem of said valve and said operating-lever, arranged to engage said cam-face, the coacting ends of the said levers arranged to move in opposite directions when operated.

3. In a pneumatic tool the combination with a head-block having an opening for receiving a valve and stem, extending all the way therethrough from one side to the other, said opening adapted at one end to receive a valve-stem, and enlarged at the other end to form a valve-chamber, and having an air-inlet duct therein entering laterally from the exterior thereof into the valve-chamber end of the opening therein, of a valve arranged in said valve-chamber and having a stem fitted to the said opening in the head-block and valve-operating means engaging the protruding end of said valve-stem substantially as set forth.

4. In a pneumatic tool the combination with a head-block having an opening for receiving a valve and stem, extending all the way therethrough from one side to the other, said opening adapted at one end to receive a valve-stem, and enlarged at the other end to form a valve-chamber, and having an air-inlet duct therein entering laterally from the exterior thereof into the valve-chamber end of the opening therein, of a valve-seat removably fitted to said valve-chamber, a valve in said valve-chamber fitted to said valve-seat and having a valve-stem fitted to the said opening in the head-block, and valve-operating means engaging the protruding ends of said valve-stem substantially as set forth.

5. In a pneumatic tool the combination with a head-block having an air-inlet duct therein, of a puppet-valve for controlling admission through said inlet-duct, said puppet-valve having a guiding-stem and a tapered neck, said tapered neck fitted to a substantially cylindrical bore in the valve-seat, and valve-op-

erating means for engaging the said valve-stem.

6. In a pneumatic tool the combination with a head-block having an air-inlet duct therein, of a puppet-valve for controlling admission through said inlet-duct, said puppet-valve having a front and rear stem guided in the said head-block, the outer ends of the guides

for both said stems being open to the atmosphere.

In witness whereof I have hereunto set my hand this 14th day of January, 1904.

CAID H. PECK.
